(57) **CLAIM**

The ornamental design for a play house, as shown and described.

DESCRIPTION

FIG. 1 is a front elevation view of a play house showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is another perspective view thereof; and,

FIG. 10 is an enlarged view of the encircled portion in FIG. 9.

The dash-dot-dash lines in FIG. 9 and FIG. 10 represent enlarged view indicators and form no part of the claimed design.

1 Claim, 10 Drawing Sheets
